UNITED STATES PATENT OFFICE.

WARREN HASTINGS MILLER, OF INTERLAKEN, NEW JERSEY.

CAMP-PACK.

1,102,200.

Specification of Letters Patent. Patented June 30, 1914.

Application filed April 19, 1913. Serial No. 762,365.

To all whom it may concern:

Be it known that I, WARREN H. MILLER, a citizen of the United States, and a resident of Interlaken, State of New Jersey, have invented certain new and useful Improvements in Camp-Packs, of which the following is a specification accompanied by drawings.

This invention relates to camp packs, but more particularly to a blanket or covering which may be used as a pack-sack, and may be combined with a sleeping mattress to form a closed sleeping envelop over the human form.

The objects of the invention are to improve upon the blanket ordinarily used, enable the blanket to be conveniently used as a pack-sack which is light in weight, and also enable the blanket to be used as one part of a sleeping-bag.

The best form of the invention known to me is shown in the accompanying drawings, in which—

Figure 1 is a plan view of the blanket; Fig. 2 is a view of the blanket made up into a pack-sack; and Fig. 3 is a side view of the combined mattress and sleeping-bag.

Referring to the drawings, the blanket A may be of convenient size and shape as shown in Fig. 1 about four feet long more or less and about three feet wide, more or less. This blanket may be used to wrap lengthwise about the middle portion of the body, if desired, in those instances in which the upper part of the body and the legs and feet are each protected as by fur, woolen or other coverings. The blanket is preferably made of waterproof material, as canvas B, on one side, lined with warm material C as mackinaw, caribou hide, or combinations of materials for warmth. The shoulder straps D are provided on the outside, and rings or fastenings E at one end to be used when the sack is formed. The longer edges of the blanket are preferably provided with the flaps or margins F for a purpose herein-after to appear and longitudinal rows of holes or other fastening devices G are shown for lacing up the sides in the form of a bag, as shown in Fig. 2, as by means of the thongs H. Holes or other fastening devices J are provided along one end for closing up

or lacing across the foot of the sleeping bag when used with a mattress. In forming the pack-sack the ends of the blanket are folded over, as shown in Fig. 2 and the sides are laced together, one end K forms the flap, and if desired, straps L may be provided to hold the flap closed, although these are not necessary. When packed the pack-sack may be swung over the shoulders as by means of the straps D.

A bag is ordinarily carried in the sack to form a sleeping mattress and when this bag O is filled with browse, moss, leaves, etc., a suitable mattress is formed. The blanket when opened out may be fastened along its longitudinal sides, as by means of the holes G and J to hooks or fastening devices P on the mattress, leaving one end of the covering open, so that a person may lie between the blanket and the mattress.

One of the great advantages of my invention resides in the fact that while ordinarily a blanket is a bulky burden, my blanket is light and combines several uses. By means of my invention the pack itself becomes the blanket and the small blanket becomes the pack. The pack-sack is of sufficient size to take a forester tent which goes in the bottom of it and which may be refolded into a small parcel. Above the tent may be stowed sweater, browse bag, mosquito cloth, etc. Then may be stowed provisions and other general duffle, camera, etc. This completes the pack, which is small and compact and the mess-kit is strapped to the top. One of the bags may be used as a pillow stuffed with leaves or moss. The blanket may be used by putting on sweater and kainiks or fur socks made out of the fur of the Arctic hare and wrapping the sleeping cloth or blanket about the middle portion of the body, but the sleeping bag may be formed in combination with the mattress.

I claim and desire to obtain by Letters Patent of the United States the following:

The combination with a sleeping mattress, of a separate and independent composite covering which may be formed into a pack sack and comprising a piece of material having fastening devices along its edges, whereby the said covering may be

folded into the form of a sack having its edges secured together, said covering being adapted to be secured to the sleeping mattress to form a closed sleeping envelop over the human form, and being provided with means attached directly thereto for carrying the pack sack.

In testimony whereof I have signed this specification in the presence of two subscribing witnesses.

WARREN HASTINGS MILLER.
